United States Patent Office.

WILLIAM W. WILCOX, OF MIDDLETOWN, CONNECTICUT.

Letters Patent No. 70,488, dated November 5, 1867.

IMPROVEMENT IN FASTENING EYELETS.

The Schedule referred to in these Letters Patent and making part of the same.

TO ALL WHOM IT MAY CONCERN:

Be it known that I, WILLIAM W. WILCOX, of Middletown, in the county of Middlesex, and in the State of Connecticut, have invented a new and useful Improvement in Eyelets; and I do hereby declare the following to be a full, clear, and exact description thereof, which will enable those skilled in the art to make and use the same, reference being had to the accompanying drawing, forming part of this specification, in which drawing—

Figure 1 represents a transverse section of this invention, showing it secured to a piece of cloth.

Figure 2 is a plan or end view of the same when detached.

Similar letters indicate corresponding parts.

This invention consists in the arrangement of a rough-surface ring between the flange of an eyelet and the material to which the same is to be fastened, in such a manner that by the rough surface of the ring the eyelet is enabled to take hold of the material with increased tenacity, and, after the eyelet has been fastened in its position, the material to which it has been fastened is not liable to get detached spontaneously. The roughness of the ring consists of a series of oblique teeth, which by their position and form are particularly adapted to retain the material to which the eyelet is fastened with great tenacity.

A represents an eyelet made of sheet metal in the ordinary manner. Between the flange *a* of this eyelet and the material to which the same is to be fastened, I interpose a ring, *b*, of iron, brass, or any other suitable material. That surface of this ring which faces the material, is provided with a series of teeth, which by preference are placed in an oblique position, as shown in fig. 2 of the drawing, or said surface may be roughened in any other suitable manner, so that when the eyelet is secured to the material, the rough surface of the ring will bite in the material, and retain the same with much greater tenacity than an eyelet applied in the ordinary manner, without the rough-surface ring. It is obvious that a rough surface of any desired description will serve in this case, but if the teeth of the ring are made oblique, as shown in fig. 2 of the drawing, they are able to retain the material to which the eyelet is fastened with the greatest tenacity, since these oblique teeth will not allow any portion of the material to strip off in a radial direction, and I prefer therefore to use such oblique teeth in my rough-surface rings.

What I claim as new, and desire to secure by Letters Patent, is—

1. The arrangement of a rough-surface ring, *b*, between the flange of an eyelet and the material to which the same is to be fastened, substantially as and for the purpose described.
2. Providing the rough-surface ring, when used in combination with an eyelet, with oblique teeth, as and for the purpose set forth.

WILLIAM W. WILCOX.
